UNITED STATES PATENT OFFICE

GUSTAV A. FORSBERG, OF CHICAGO, ILLINOIS, ASSIGNOR TO GULBRANSEN COMPANY,
OF CHICAGO, ILLINOIS, A CORPORATION OF ILLINOIS

PEDAL CONSTRUCTION AND MOUNTING

Application filed February 20, 1928. Serial No. 255,590.

This invention relates to player pianos, and more particularly to the construction and mounting of the pedals for operating the exhaust bellows of the exhaust power unit.

In the application of Axel G. Gulbransen for player piano, filed August 3, 1927, Serial No. 210,224 is disclosed a novel arrangement and construction of the power exhaust unit and the pedals for operating the same where-
10 by the pedals may be disposed in the same manner as the pedals of a hand played piano of standard type, the tone pedal being at the center of the toe rail and the operating ped-
als being disposed at opposite sides of the tone
15 pedal. This arrangement has proved to be highly efficient both from the æsthetic stand-
point and from the standpoint of operation, though I have found that, from the standpoint of operation, the construction of the operating
20 pedals and the method of mounting of the same can be improved upon. These pedals are operated by the feet being alternately de-
pressed and released, as is well understood in the art. With pedals of the type disclosed
25 in the copending application of Axel G. Gul-
bransen, above identified, the heel of the operator's shoe rests upon the floor and pro-
vides a fulcrum point for movement of the foot in playing of the instrument. In the
30 natural up and down movement of the foot in alternately depressing and releasing the ped-
als, it is desirable that the upward move-
ment be not sufficiently great to tend to place the leg muscles under strain, thus quickly

35 tiring the operator. I have found that the most suitable position of the foot with the toe pressure thereof bearing upon the foot receiving portion or element of the pedal and the heel upon the floor, is at an angle of approximately 40 degrees to the floor surface. With the pedals mounted in such manner as to give this angle, sufficient throw of the pedal to properly operate the exhaust bellows of the power unit is obtained, and tiring of the leg muscles due to unnatural strain is avoided. At the initiation of the depression of the pedal there is a natural forward thrust of the toe portion of the foot due to the swinging movement of the foot about the 40 point of contact of the heel of the shoe with

the floor surface. By mounting the pedal for limited longitudinal movement to accommodate this natural forward thrust of the foot the point of the foot at which the pressure is applied to the pedal is not shifted but remains constant in the operation of the pedals and this is also of material assistance in preventing tiring of the foot muscles due to shifting of the point of application of pressure to the pedals, such as inevitably occurs where provision is not made for the limited longitudinal movement of the pedal referred to. A further object of my invention is to provide a flat foot plate suitably connected to the pedal to accommodate the compound movement thereof, this plate providing at all times an appreciable area of contact with the foot for applying pressure to the outer end of the pedal. Further objects and advantages will appear from the detailed description.

In the drawings:

Fig. 1 is a fragmentary sectional view through the lower portion of a player piano case illustrating the method of mounting and operation of my pedal construction; 75

Fig. 2 is a plan view of the operating pedals and associated parts taken in the plane of the upper edge of the toe rail;

Fig. 3 is a fragmentary side view of one of the pedals partly broken away and in section:

Fig. 4 is an outer end view of one of the pedals:

Fig. 5 is a section taken substantially on line 5-5 of Fig. 4 looking down on the outer end portion of one of the operating pedals. 85

end portion of one of the operating pedals. My invention is intended particularly for use in connection with a power exhaust unit indicated in its entirety by 1 which is mounted in the lower portion of casing 2 of a player piano of known construction such as that disclosed in the application of Axel G. Gulbransen above identified. The case 2 includes a removable lower front board 3, a toe rail 4, and a base board 5 closing the lower end of the case. The unit 1 includes an equalizing bellows 6 secured to a pair of exhaust bellows 7 which communicate with the equalizer 6, these exhaust bellows being sup- 90 95 100

ported by brackets 8 secured thereto and to the base board 5. Each of the bellows 7 is provided with an arm 9 extending therefrom, between which and the operating pedal is confined a connecting rod 10. The exhaust bellows is normally held in collapsed condition by a tension spring 11 having its ends secured to brackets 12 which are secured to the upper and lower leaves of the bellows. 5 The intake of the equalizer 6 is connected by a tube 13 to the channel board of the instrument and, if desired, to the roll motor, this connection being made through a suitable throat structure and governor and associated parts as is well understood in the art. The 10 construction and operation of the power unit and associated parts is disclosed fully in the copending application of Axel G. Gulbransen previously referred to, and need not be illustrated or described in detail here. The 15 exhaust power unit may be employed to operate the roll motor as well as to exhaust the channel board, as stated, though I prefer to employ this unit for exhausting the channel board only, the means for winding and re-winding the music sheet being operated from any other suitable separate source of power. Such means is disclosed in the copending application of Axel G. Gulbransen for player piano, Serial No. 163,016, filed January 24, 1927, and in the copending application of Arthur H. Boettcher for player piano, Serial No. 163,898, filed January 27, 1927. 20

The connecting rod 10 is provided, in each 25 end thereof, with a pin 14. The pin at the upper end of the rod passes through a felt bushing 15 extending through an opening 16 at the inner end of arm 9. A felt disc 17 is secured to the upper end of rod 10 and provides a cushioning element between the 30 same and the arm 9. A second felt bushing 15 is provided about the pin 14 at the lower end of rod 10 and extends through an opening 18 at the inner end of an L-shaped extension 19 of an operating pedal 20. A second felt disc 17 is interposed between the 35 upper face of member 19 and the lower end of rod 10. The openings 16 and 18 are of sufficient extent to permit relative movement between the rod 10 and arm 9 and member 19 to accommodate raising and lowering of the pedal 20 in the operation of the 40 exhaust bellows 7, and the bushings 15 and discs 17 prevent any undesirable looseness or metallic rattle between the pedals and the associated means for operating the 45 bellows.

Each of the pedals 20 has an outer or main portion which includes a shank 21 to which the L-shaped extension 19 is secured by cap-screws 22. This shank extends through an opening 23 through the toe rail, which opening is felted and is provided at its bottom with an outwardly tapering felt pad 24, as 50 illustrated, to cushion movement of the pedal.

The shank 21 is provided with an upwardly projecting guard element 25 adjacent the outer face of the toe rail, which guard element functions in a known manner to prevent contact of the player's toe with the rail 70 4. Upon depression of the outer end of the pedal 20 the rod 10 is raised so as to extend the bellows 7, exhausting the equalizer 6. Upon release of the pressure on the outer end of the pedal the top leaf of the bellows 7 is returned to lowered position through the action of the tension spring 11 thus depressing the inner end of the pedal and raising the outer end thereof into normal operating 75 position. 80

Shank 21 of the pedal is provided at its outer end with two spaced rounded lugs 26 separated by a slot forming a rectangular recess 27. An element 28 straddles the outer end of this recess and extends outwardly from the outer end of shank 21, the upper face 29 of this element being disposed at an inclination to the horizontal of approximately 40 degrees. As will be noted more clearly from Fig. 3, the recess 27 is arched in the direction of its length and extends beneath and partially about a pintle screw 30 which extends through the lugs 26 and through ears 31 formed integrally with and depending from a foot plate 32, these ears being disposed closely adjacent the outer faces of the lugs 26. A wire spring 33 is mounted about pintle 30 between the lugs 26 and has its lower arm 33a seated in a groove 34 in the upper face of shank 21 and extending from the inner end of recess 27. The other arm 33b of spring 33 bears against the under face of plate 32 above and inside of pintle 30. This spring serves to urge the foot plate 32 outwardly about the pintle 30 so as to normally hold the under face of this plate in contact with the inclined face 29 of element 28. The foot plate 32 is thus normally disposed at what I have found to be the proper angle for most efficient operation of the pedal without tiring of the leg muscles due to subjecting them to unnatural strain. 100

With the heel of the shoe resting upon the floor as a fulcrum point, when pressure is exerted on the foot plate 32 by the toe portion of the foot, there is, at the initiation of the pressure on the outer end of the pedal, a natural forward thrust effect of the foot and, if this movement is not accommodated, the foot is subjected to unnatural strains with the result that the foot muscles are quickly tired. During continued downward movement of the outer end of the pedal, if the pedal be held against longitudinal movement, the outer end of the pedal, in effect, moves toward the heel of the foot due to the arcuate travel of this outer portion caused by swinging of the pedal about its pivot. As a result, it is necessary that there be relative 110 120 130 140 150 160 170 180 190 200 210 220 230 240 250 260 270 280 290 300 310 320 330 340 350 360 370 380 390 400 410 420 430 440 450 460 470 - sliding movement between the foot and the foot receiving element for applying pressure to the pedal. This means that the point of application of pressure by the foot shifts 5 from one position to another during operation of the pedal thus subjecting the foot muscles to shifting and unnatural strains and quickly tiring them. I avoid these objections by mounting the operating pedals 10 in such manner as to accommodate the initial forward thrust of the foot and permit limited longitudinal movement of the pedal whereby the point of application of pressure of the foot remains constant.
- 15 Referring more particularly to Figs. 1 and 2, each of the pedals 20 is supported from a substantially L-shaped bracket 34 secured by leg screws 35, or in any other suitable manner, to the base board 5. Outer supporting 20 links 36 are pivoted at their lower ends, at 37, to the lower horizontal arm of brackets 34, the base board 5 being provided with a recess 38 in its upper face accommodating the lower ends of these links. Links 36 are 25 pivoted at their upper ends, at 39, to shanks 21 of pedals 20 the pivot 39 being disposed between the cap screws 22. The extension 19 of the pedal is provided at its inner end with a depending vertical arm 40 formed integral 30 therewith. The lower end of this arm is connected by a pair of links 41 to the upper end of the vertical arm 34a of bracket 34, the lower ends of links 41 being pivoted at 42 to arm 40 and the upper ends of these links 35 being pivoted at 43 to arm 34a. In the operation of the pedal, with the foot F in operating position with the toe portion thereof resting upon the plate 32 and the heel resting upon the supporting surface or floor at 40 a, the foot is disposed at an angle of approximately 40 degrees to the floor, this angle being such as not to subject the foot or leg muscles to unnatural strain. When the pedal is depressed by exerting pressure on the plate 45 32, the pintle 30 moves through the arc b—c. During this movement of the outer end of the pedal, the shank 21 swings about pivot 39 swinging the links 41 about pivot 43 into substantially horizontal position, caus- 50 ing the pivot 42 to move through the arc e—d and causing a consequent slight rearward movement of the pivot 42 permitting rearward or inward movement of the pedal in a longitudinal direction. This causes 55 shifting of the pivot 39 rearwardly a slight distance so that the pedal is capable of a compound movement, that is, it has a swinging movement about the pivot 39 and has a simultaneous longitudinal movement which 60 is limited in extent by the links 41 and the associated parts. As a result of this movement of the pedal, the forward thrust of the foot in depressing the pedal is accommodated, no relative sliding movement between the 65 foot and the foot plate or pressure apply-
- ing element is necessary, and the point of application of pressure by the foot remains constant eliminating tiring of the foot muscles such as results from shifting this point of application. This has the advantage that 70 the foot may be so placed when starting to operate the pedal as to apply pressure on the foot plate to the best advantage and with least effort, and the necessity for shifting the foot relative to the pedal is eliminated.
- 75 In practice the pedals 20 are disposed at opposite sides of and equi-distant from a tone or sustaining pedal 44 which operates through the toe rail 4 and is secured at its inner end to a rod 45 which has connection with the damper rail, this rod being rockably mounted in blocks 46 secured to the base board 5. This pedal and its function in operating the damper rail is well known to those skilled in the art. The construction and operation 80 of the tone pedal is similar in all respects to that of the tone pedal disclosed in the co-pending application of Axel G. Gulbransen for player piano, Serial No. 210,224, filed August 3, 1927, previously referred to. The 85 foot plates 32 are flat and preferably have their upper faces knurled to prevent slipping, these plates being of sufficient area to provide an appreciable surface of contact for the application of pressure by the foot 90 while eliminating interference by the tone 95 pedal 44 with the operation of the operating pedals 20. By constructing and forming the operating pedals in the manner illustrated and described, I provide a thoroughly 100 practical and highly efficient player piano in which these pedals are arranged similarly to and closely simulate the pedals of the standard type of hand played piano.
- 105 What I claim is:
1. In a player piano, an exhaust power unit, a pair of operating pedals pivoted intermediate their ends, operating connections between said unit and the pedals, and foot plates hinged to and disposed above the outer ends of the pedals and having rocking motion with respect thereto in the operation of the pedals. 110
- 115 2. In a player piano, an exhaust power unit, a pair of operating pedals pivoted intermediate their ends, operating connections between said unit and the pedals, foot plates hinged to and disposed above the outer ends of the pedals, yielding means urging the plates in one direction, and means limiting 120 movement of the plates in such direction.
- 125 3. In a player piano, an exhaust power unit, a pair of operating pedals mounted for rocking and limited longitudinal movement, operating connections between said unit and the pedals, and foot receiving elements hinged to the outer ends of the pedals and having rocking motion with respect thereto in the operation of the pedals, said elements being 130 free from said connections.

4. In a player piano, an exhaust power unit, a pair of operating pedals mounted for rocking and limited longitudinal movement, operating connections between said unit and the pedals, foot receiving elements hinged to the outer ends of the pedals, yielding means urging said elements outwardly of the pedals, and means limiting outward movement of the foot receiving elements.
- 10 5. In a player piano, an exhaust power unit, a pair of operating pedals mounted for rocking and limited longitudinal movement, foot receiving elements hinged to the outer ends of the pedals and disposed above the same, yielding means urging said elements outwardly of the pedals, and means limiting outward movement of the foot receiving elements and normally holding them at an inclination downwardly and outwardly of the pedals.
- 15 6. In a player piano, an exhaust power unit, a pair of pedals, substantially L-shaped supporting brackets, said pedals having downwardly extending arms at their inner ends, links connecting the lower ends of said arms to the upper ends of the vertical arms of the brackets, links connecting the horizontal arms of the brackets to the pedals, and operating connections between the pedals and said power unit.
- 20 7. In a player piano, an exhaust power unit, a pair of pedals, substantially L-shaped supporting brackets, said pedals having downwardly extending arms at their inner ends, links connecting the lower ends of said arms to the upper ends of the vertical arms of the brackets, links connecting the horizontal arms of the brackets to the pedals, operating connections between the pedals and said power unit, and foot plates hinged to the outer ends of the pedals.
- 25 8. In a pedal construction, a shank, a foot plate hinged to the outer end of the shank, yielding means urging the plate toward the outer end of the shank, and means limiting outward movement of the plate and cooperating with said yielding means to normally hold the plate at an inclination downwardly toward the outer end of said shank.
- 30 9. In a pedal construction, a shank, a flat foot plate hinged to the outer end of the shank, an element extending from the outer end of the shank outwardly beyond the hinge axis of the plate and having its upper face inclined downwardly away from said shank, and yielding means urging the plate outwardly of the shank and normally holding said plate with its under face seating upon the upper face of said element.
- 35 10. In witness whereof I hereunto subscribe my name this 15th day of February, 1928.

GUSTAV A. FORSBERG.
